(57) **CLAIM**

The ornamental design for a sink, as shown and described.

DESCRIPTION

In a preferred embodiment, the nature of this product is as a plumbing fixture primarily useful for washing food and implements therefor.

FIG. 1 is a left, top, front perspective view of a sink embodying our new design;

FIG. 2 is a top plan view thereof;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a bottom plan view thereof;

FIG. 8 is a cross-sectional view taken along line 8—8 of FIG. 2; and,

FIG. 9 is a right, top, front perspective view of a second embodiment, the top plan view being a mirror image of that shown in FIG. 2, the front elevational view being a mirror image of that shown in FIG. 3, the right side elevational view being a mirror image of that shown in FIG. 4, the rear elevational view being a mirror image of that shown in FIG. 5, the left side elevational view being a mirror image of that shown in FIG. 6, and the bottom plan view being a mirror image of that shown in FIG. 7.

The broken line representations of holes in FIGS. 1, 2, 7, and 9, and of support structure in FIGS. 1 and 3—9, are for the purpose of illustration only, and form no part of the claimed design.
